CAN CRUSHING DEVICE

Carl G. Danielson, Rocky River, Ohio, assignor
to Danco Metal Products, Inc., Westlake, Ohio,
a corporation of Ohio

Application September 9, 1950, Serial No. 184,041

1 Claim. (Cl. 153—10.5)

1

This invention relates to means for crushing cans and the like in order to minimize the storage space necessary for empty containers until final disposition of them.

An object of this invention is to provide means for crushing cans or the like which may be operated efficiently by hand to reduce such a container to a compact and substantially flattened form.

Another object is to provide means to adapt such a device to operate in conjunction with a receptacle in which the crushed containers are placed for storage purposes.

Further objects and advantages will become apparent from the following description and drawing of a preferred embodiment of the invention.

In the drawing, in which like numerals refer to like parts throughout,

Fig. 1 is a perspective view of one embodiment of the invention;

Fig. 2 is a front view of a portion of the device showing in dotted lines a can being crushed;

Fig. 3 is a vertical sectional view taken on the line 3—3 of Fig. 1;

Fig. 4 is a perspective view showing an angle strip used for mounting the device on a drum receptacle;

Fig. 5 is a top view of an open top drum with the device mounted thereon, only the base portion of the device being shown; and

Fig. 6 is a fragmentary vertical sectional view taken on the line 6—6 of Fig. 5.

In the present era when so great a percentage of foods and articles of all sorts are sold in tin can containers or the like, the disposal or storage until disposal of used containers can and does become troublesome. The problem of storage may become particularly acute in situations where many large volume cans are emptied each day such as in a service station where motor oil is so packaged. In some localities, empty containers must be carried many miles to a disposal area and it is therefore exceedingly desirable to reduce the volume of the empty containers to a minimum.

In general, the present invention relates to a crushing device comprising a hand-operated plunger which carries a crusher plate on its lower end. Also, a novel method of mounting is provided for placing the device in operative position over a receptacle.

Referring to the drawing, the device comprises a metal frame structure having a base 10, a rear wall 11, and side walls 12, the side walls being of generally triangular form. The various parts of the frame structure may be made separately and suitably joined together or, as in the present in-

stance, the entire structure may be cast as an integral unit thereby providing a strong durable structure. The angle members 13, welded or otherwise secured to the base 10, extend from front to back thereof, and serve a purpose to be later described. The frame structure also has a pair of laterally spaced flanges 15 which are made integral with or are secured to the rear wall 11. The flanges extend forwardly therefrom and have a front channel member 16 mounted between them by means of the bolts 17 and a short rear channel member 18 welded therebetween. An upright plunger 20 having rack teeth 21 cut therein is retained between the channels 16 and 18 and is provided at its lower end with a can-engaging crusher plate 22. An angle member 23 is secured to the lower side of the crusher plate and extends from front to back thereon.

The plunger 20 and its attached crusher plate 22 are raised and lowered by means of a pinion gear 25 keyed to a shaft 26 which is journaled on the flanges 15. A hand lever 27 is mounted on one end of the shaft 26 by means of the bolt and washer combination 28. Therefore, when an operator pulls the lever 27 forward, the shaft 26 and the pinion keyed thereto will rotate in a counter-clockwise direction (Fig. 3), and the teeth of the pinion 25 meshing with the rack teeth 21 cause the plunger and crusher plate to be lowered. By using a hand lever 27 of proper length, a force sufficient to flatten a large can between the crusher plate 22 and the base 10 may easily be provided without strenuous effort on the part of an operator. As previously mentioned, the crusher plate carries the angle member 23 and the base 10 has the similar angle members 13 attached thereto; the angle members 13 prevent a can from rolling when placed on the base 10, and the angle member 23 aids in initiating the crushing operation.

As shown in Fig. 1, apertures 30 are provided in the rear wall 11, so that the device may be suspended from a suitable support by bolts or the like extending through the apertures. To facilitate the removal of crushed containers, an opening 31 is provided in the rear portion of the base 10. Thus a flattened can may be pushed rearwardly by an uncrushed can being placed in the device and fall into a suitable collector.

In Figs. 4, 5 and 6, there is illustrated means to mount the device on an open top collecting drum, designated generally by the numeral 33, having a top bead or flange 34. The mounting 55 means comprises two angle strips 35 which are

attached one to each side wall 11 by means of bolts 36 through mating apertures 37 and 38. The rear end of each angle strip 35 is bent under as at 39 to form a hook which engages the drum rim bead 34, and the front end of each is bent downwardly as at 40 and threaded to receive a thumb screw 41. It is apparent that when the thumb screws 41 are tightened, the device is securely attached to the collecting drum, and, therefore, used containers may be crushed and deposited in the collector in virtually a single operation with a consequent saving of time and effort.

The device described herein is simple in construction, durable and efficient and will quickly reduce a tin can or the like to approximately one-seventh its original volume. Various changes, of course, may be made by one skilled in the art without departing from the spirit of the invention or the scope of the appended claim.

What I claim is:

A can crushing device, comprising a frame structure having a generally horizontal base plate and a generally vertical rear wall, a pair of generally vertical flanges carried by and extending forwardly from said rear wall in laterally spaced, generally parallel relation, a pair of generally vertical, oppositely extending channel members carried by said flanges in the space therebetween and spaced apart to provide a generally verti-

cal passageway, a plunger in said passageway provided with rack teeth along a substantial portion of its length, a can crushing plate carried by said plunger at the lower end thereof, a pinion journaled in said flanges and disposed in the space therebetween for meshing engagement with the rack teeth of said plunger, one of said channel members being of reduced length to permit such meshing engagement, and a lever for rotating said pinion to thereby raise and lower the plunger and the can crushing plate carried thereby relative to the base plate of the frame structure.

CARL G. DANIELSON.
